UNITED STATES PATENT OFFICE.

GEORGE WILLIAM GREEN, OF WOY WOY, NEW SOUTH WALES, ASSIGNOR
TO THOMAS EDWARD WOODHAMS NOYES, OF SYDNEY, NEW SOUTH
WALES.

TRAY FOR INCUBATORS.

SPECIFICATION forming part of Letters Patent No. 685,134, dated October 22, 1901.

Application filed October 25, 1900. Serial No. 34,354. (No model.)

To all whom it may concern:

Be it known that I, GEORGE WILLIAM GREEN, carpenter, a subject of the Queen of Great Britain, residing at Woy Woy, in the 55 British Colony of New South Wales, have invented new and useful Improvements in Trays, Drawers, and other Egg-Frames for Incubators, of which the following is a specification.

- 10 This invention relates to improvements in trays, drawers, and other egg-frames for incubators; and it has been specially devised so that the eggs in incubators may be easily and quickly changed or turned without danger to them or the embryo. At the same time it allows a flat and smooth and unconfined surface to be available for the hatched chickens and such a surface as is easily cleansed and easily renewable.
- 15 A tray or drawer or other egg-frame for incubators constructed according to this invention has as its essential feature a false bottom adapted to be drawn to and fro below the eggs resting upon it in confined spaces, so that upon its movement the eggs will be turned or revolved more or less thereon. In the construction of such a tray, drawer, or frame it is preferred to use textile fabric as such false bottom and to arrange that it
- 20 will wind upon rollers (upon their revolution by a key) at opposite ends of the tray, drawer, or frame. The confined spaces for the eggs are provided by a secondary frame taking over the false bottom, such secondary frame being removable, so as to leave a clear space for the use of the hatched chickens and so that the false bottom may also be removed and washed or renewed.

In order that this invention may be clearly understood, reference will now be made to the drawings herewith, in which—

Figure 1 is a perspective view of a tray, drawer, or egg-frame for an incubator constructed according to this invention. Fig. 2 is a cross-section of the same, and Fig. 3 a plan of one of the rollers for holding and moving the false bottom.

A is the main frame, adapted to fit into the incubating-chamber. The bottom A'—say of 50 woven wire—is attached to the main frame A

by frame or slats A², screwed thereto. At one end inside said frame A are U-shaped receptacles or bearings B' and at the other end corresponding bearings C' for the reception of rollers B and C, respectively. Either end of these rollers is adapted to have fitting thereon or therein a key or turning-lever, as shown in Fig. 3.

B³ is a square end for a socket on the key F, (shown in use in Fig. 1,) and B² is a socket end for a key end. The key is passed through an orifice (closed, as desired) in the wall of the incubating-chamber and through holes A³ in the frame A. To these rollers are attached, by means of V-grooves and slats, as 65 shown, or by other means, the ends of a slightly open-work woven strip—say of cotton—forming the false bottom D. This strip, though apparently solid, as shown, is preferably of such texture that the heated air of 70 the incubating-chamber will have free passage therethrough. It is also of such a length that there will be one or two wrappings around one of the rollers—that is, it is of sufficient excess length to insure not less than 75 a full revolution of an egg resting thereon. Fitting within the frame A and the bearings B' and C' is the secondary frame E, having cross-pieces or corrugated strips E' dividing the whole into egg-spaces, so as to prevent 80 eggs in such spaces from traveling with the moving false bottom. This frame E rests at the sides on the bottom A' and may have a clearance for said false bottom at the ends, though it is not of sufficient weight to be an 85 obstacle to the movement, even if it rested upon said false bottom. It is easily lifted from and replaced within the frame A.

Ready for use the tray or frame is as shown in Fig. 1, with the false bottom D taut across 90 the bottom A' and with one end fully rolled around one of the rollers B or C. The eggs, whether marked or not is immaterial, though they are preferably marked, are placed in the spaces of the frame E. During the process of 95 incubation the eggs are “changed” or turned a part of a revolution at regular intervals, as desired, (say once daily or twice a day,) until within three days or thereabout of the hatching, when they are then left alone; but the 100

secondary frame E is removed to allow of a flat and smooth surface being ready for the chickens. This changing or turning is achieved by revolving or partly revolving one of the rollers B and C and winding false bottom D thereon, as may be clearly seen from the foregoing description. This winding and unwinding of the false bottom draws it across the frame and causes each egg confined in its own space to partly revolve by reason of the movement of said false bottom beneath it.

Many and various devices for carrying this invention into practical operation might be devised (though the best now known is described herein) without departing from the nature and essence of these present improvements, and it is to be particularly understood that the said invention is not confined to the precise manner nor the details thereof herein set forth and described of constructing these said improvements.

Having now particularly described and ascertained the nature of my said invention and

in what manner the same is to be performed, I declare that what I claim is—

In an incubator, the combination with a frame, a bottom therefor, a false bottom mounted thereon, and means for moving the said bottom, of a secondary frame mounted upon said false bottom, and a series of transversely-extending corrugated strips, standing on edge, rigidly secured to the inner face of the sides of said stationary frame and arranged in pairs with the backs of the corrugations of each of said pair of strips engaging each other to form parallel rows of communicating egg-spaces with substantially elliptical-shaped side walls.

In testimony whereof I have signed my name to this specification in the presence of two subscribing witnesses.

GEORGE WILLIAM GREEN.
